SWIZZLE STICK

Norbert Leslie Silvas, Greenwich, Conn., assignor to Sign & Marketing Corporation

Filed Mar. 9, 1971, Ser. No. 122,644

Term of patent 14 years

Int. Cl. D7—04

U.S. Cl. D94—3

FIG. 2   FIG. 1   FIG. 3

FIG. 5

FIG. 4

FIG. 6

FIG. 1 is a top plan view of a swizzle stick showing my new design;

FIG. 2 is an edge elevation of the swizzle stick of FIG. 1;

FIG. 3 is a longitudinal sectional view along the lines 3—3 of FIG. 1;

FIG. 4 is a perspective view of the swizzle stick of FIG. 1;

FIG. 5 is a sectional view on an enlarged scale taken on line 5—5 of FIG. 1; and

FIG. 6 is a sectional view on an enlarged scale taken on line 6—6 of FIG. 1.

I claim:

The ornamental design for a swizzle stick, as shown.
